UNITED STATES PATENT OFFICE.

JAMES H. MONTGOMERY, OF BUTTE, MONTANA.

GREASE-DISPENSING APPARATUS.

1,306,607.

Specification of Letters Patent. Patented June 10, 1919.

Application filed August 23, 1916. Serial No. 116,480.

To all whom it may concern:

Be it known that I, JAMES H. MONTGOMERY, a citizen of the United States, residing at Butte, in the county of Silver Bow, State 5 of Montana, have invented certain new and useful Improvements in Grease-Dispensing Apparatus, of which the following is a description, reference being had to the accompanying drawing, and to the figures of reference marked thereon.

My invention relates to new and useful improvements in grease dispensing apparatus.

An object of my invention is to provide 15 a dispensing apparatus of this character, which can be readily attached to a receptacle such as a barrel, and the entire contents of the receptacle dispensed in predetermined amounts with each operation of 20 the lever.

A further object of my invention is to provide an apparatus of this character which forms a support for the receptacle and having details of structure and combination of parts hereinafter more fully described.

In the accompanying drawings:—

Figure 1 is a transverse vertical sectional view of a receptacle showing my improved dispensing apparatus applied thereto;

Fig. 2 is a transverse sectional view taken on the line $x-x$ of Fig. 1;

Fig. 3 is a transverse vertical sectional view taken on the line $z-z$ Fig. 2 at right angles to Fig. 1;

Fig. 4 is an enlarged perspective view of the follower operating means in their separated relation;

Fig. 5 is an enlarged perspective view of 40 the grease receiving and measuring cylinder;

Fig. 6 is a vertical longitudinal sectional view of the flexible connecting member of the follower operating rod;

Fig. 7 is a vertical transverse sectional view of Fig. 5; and

Fig. 8 is a vertical transverse sectional view showing the inner cylinder in its rotated position when dispensing the grease.

Fig. 9 is a transverse horizontal sectional view showing means for connecting the arm to the barrel;

Fig. 10 is a bottom plan view showing the cover for the opening in the bottom of the 55 barrel.

Referring now to the drawings, 1 represents the receptacle from which the grease is to be dispensed and which is preferably in the form of a cylindrical barrel and is the original container in which the grease 60 is shipped from the factory. The bottom 2 of the barrel is provided with an upwardly turned flange 2' secured to the inside of the barrel and provided with an elongated slot 3 extending partially across the same and 65 through which the grease is forced into the dispensing and measuring cylinder as will be later described. The slot 3 is closed by a cover 3' pivoted at 4' and held in position by screws 5' and whereby the grease is held 70 in the barrel during the shipping thereof.

The dispensing apparatus consists of a circular plate 4 to correspond with the shape of the bottom of the receptacle and is provided with an upwardly extending annular 75 flange 5 which surrounds the lower end of the receptacle and is secured thereto by means of set screws 6 which pass through the flange 5 and engage the outer face of the barrel. The said plate 4, as shown is spaced 80 from the bottom of the barrel and is provided with a downwardly bulged portion 8 which corresponds in size with the elongated opening 3 in the bottom 2 of the receptacle. The plate 4 as shown in Figs. 1 and 3 of the 85 drawings is spaced some distance below the bottom of the receptacle and on each side of the downwardly bulged portion 8, is provided the upwardly extending flanges 8' 90 which engage the lower face of the bottom 2 on opposite sides of the opening 3.

Within the downwardly bulged portion 8 of the plate 4 is a cylindrical member 9 having one end open and the opposite end contracted as indicated at 10 and to which is 95 connected a flexible pipe 11 whereby the grease is forced to the desired point as will be hereinafter more fully described.

The cylindrical member is secured to the plate 4 in any desired manner and has its 100 upper face cut away as indicated at 12 whereby the grease can enter the same through the opening 3 in the bottom of the receptacle. Within the cylindrical member 9 is a second member 13 having one end closed as indicated at 14 and its opposite end open and communicating with the contracted portion 10 of the outer cylindrical member. The inner member is provided with a cutaway portion 15 corresponding 110

with the cutaway portion 12 of the outer member and registering as shown in Fig. 5 of the drawings, so that the grease can enter the inner cylinder.

5 The end 14 of the inner member 13 is provided with a circular opening 16 and communicating therewith is a rectangular opening 17. Within the inner cylindrical member or pump barrel is a piston 18 which has its piston rod 19 extending out through the opening 16 in the end 14 of the inner cylindrical member. The piston rod is provided with a fin 20 which is spirally arranged adjacent the piston as indicated at 21, the remainder of the fin extending parallel with the piston rod. The piston rod beyond the spirally arranged portion of the fin is rotatably and longitudinally mounted in the bearing 22 carried by the upper face of the plate 4.

Secured to the side of the receptacle 1 is a narrow plate 23 which has its upper end turned downwardly over the upper end of the receptacle and its lower end riveted or otherwise secured to the flange 5 of the plate 4. The plate 23 about midway its length is provided with a guideway 23' in which is removably mounted an outwardly extending arm 24, to which is intermediately pivoted at 26 the lever 25. A suitable stop in the guideway serves as a support for the head of the arm 24. The lower end of the lever 25 has a slot 27 into which extends a pin 28 carried by the outer end of the piston rod 19 and whereby the piston rod is moved in and out in a straight horizontal line.

Carried by the upper face of the plate 4 are two straps 29 and 30 which support a barrel 31 in which is arranged a coil spring 32. Passing through said barrel 31 is a rod 33 which has its outer end turned laterally and outwardly as indicated at 34' so as to bring it close to the piston rod 19. The piston rod 19 is provided with a lateral extension 34 which engages the portion 33 of the rod and moves it inwardly. One end of the spring 32 is connected at 32' to the left hand end of the barrel, as shown in Fig. 6, and the opposite end is connected to the rod 33 at 33', which passes outwardly through the collar 35, carried by the barrel 31. The spring normally holds the rod 33 forced to the left, as shown in Fig. 6 of the drawings. The inner end of the rod 33 has pivotally mounted thereon the pawl 36 which engages the ratchet 37 keyed upon the shaft 38. The pawl 36 rests upon the upper face of the plate 4 and the shaft 38 extends through the bottom 2 of the receptacle and has threads thereon. Within the barrel above the grease is a follower 39 which has a threaded opening 40 through which the shaft 38 is screwed and at the lower end of the shaft is a ratchet 37, whereby the follower is moved downwardly by the rota-

tion of the ratchet as will be later described. The outer periphery of the follower has a leather or rubber ring 41 which engages the inner face of the receptacle and forces all of the grease down and prevents any from passing upwardly above the follower. The pawl 36 is so constructed that when the device is attached to the barrel upon the inward movement of the rod 33 the pawl engages the ratchet 37 and rotates it and upon the backward movement the pawl rides over the teeth of the ratchet and assumes a position to again turn the ratchet upon the forward movement of the rod. The spring 32 moves the rod to the left so as to bring the pawl into operative position and thus the follower is forced downwardly a slight distance with each movement of the piston rod lever 25. The threaded bar 38 is first inserted through the bottom of the barrel 31 and forced through the grease to the upper end of the barrel, when the follower is placed in the barrel with the opening above the rod. When the device is applied to the original container, such as a barrel, a rod 39 or other member may be placed in the opening in the end of the barrel and extends through the opening in the follower to hold the follower in its proper position while the barrel is being filled with grease. It might be, however, that the rod and ratchet would be arranged in the barrel and sold as a part thereof.

The lower face of the plate 4 is provided with two cleats 42 and 43 by means of which the axle 44 carrying the wheels 45 are secured to the device. This shaft, as shown, is at one side of the center of the grease receptacle so that the same will not tilt. The bottom plate 4 has secured thereto a caster 46 whereby the device is mounted so that it can be rolled from place to place.

When it is desired to dispense grease from the receptacle, the lever 25 is in the position shown in Fig. 1 of the drawings and the cylinder members 9 and 13 are in the position shown in Figs. 1 and 5 and the follower has forced the grease down through the opening 3 into the inner cylinder 13. The lever 25 is drawn outwardly which forces the piston rod 19 inwardly. The spiral portion 21 of the fin 20, traveling to the right in the slot 17 causes the inner member 13 to make one half a revolution which brings the opening 15 at the lower end, as shown in Fig. 8. By this time the straight portion of the fin has reached the slot and the continued movement of the piston rod holds the two members in the position shown in Fig. 8. The piston 18 forces the grease out of the member 13 through the contracted end 10 to the pipe 11 and to the desired point. When the piston has about reached its extreme movement to the right, the projection 34 130

engages the rod 33 and causes the pawl to rotate the ratchet 37 and the worm shaft 38 forces the follower down a very small distance to compress the grease. The lever 25 is moved inwardly and the rod 33 by the spring 32 is moved outwardly carrying with it, the pawl so that it is ready for another operation.

When the spiral portion of the fin 20 reaches the opening 17, the inner cylinder 13 is caused to rotate one half a revolution to bring the openings 12 and 15 opposite and the grease under compression enters the inner member and the machine is ready for another operation.

Having thus described my invention, what I claim as new and desire to secure by Letters Patent, is:—

1. In an apparatus of the character described, the combination with a receptacle, of a support detachably secured to the receptacle, a cylinder carried by the support and in communication therewith, means for forcing the grease from the receptacle to the cylinder, a piston for forcing the grease from the cylinder, and means operated by the forward movement of the piston for closing the communication between the cylinder and the receptacle during the time the piston is forcing the grease from the cylinder.

2. In an apparatus of the character described, the combination with a receptacle having an elongated opening, a stationary cylinder having an opening corresponding with the opening in the receptacle, a rotary cylinder within the stationary cylinder and having a corresponding opening, a piston within the rotary cylinder and held against rotation, a piston rod carried by the piston and a spiral fin carried by the piston rod and adapted to rotate the rotary cylinder to bring the registering openings out of alignment during the movement of the piston for forcing the grease from the cylinder.

3. In an apparatus of the character described, the combination with a receptacle having an elongated opening, a stationary cylinder having an opening corresponding with the opening in the receptacle and communicating therewith, a rotary cylinder in the stationary cylinder and having an opening corresponding with the opening in the stationary cylinder, a piston in the rotary cylinder, a piston rod connected to the piston and extending through the head of the rotary cylinder, a spiral fin carried by the piston rod adjacent the piston and having a straight portion throughout the remainder of the piston rod passing through an opening in the head of the rotary cylinder, means for reciprocating the piston rod, whereby the cylinder is rotated for bringing the openings out of alignment during the forcing movement of the piston, and

means operated by the piston rod for forcing the grease from the receptacle to the rotary cylinder.

4. In an apparatus of the character described, the combination with a receptacle having an elongated opening, a stationary cylinder having an opening corresponding with the opening in the receptacle and communicating therewith, a rotary cylinder having an opening corresponding with the opening in the stationary cylinder, a reciprocating piston in the rotary cylinder and held against rotation, a piston rod operating the piston, means operated by the reciprocation of the piston rod for rotating the cylinder during the outward movement of the piston, a follower in the receptacle, a worm geared to the follower and passing through the receptacle, a ratchet carried by the worm below the receptacle, a rod adjacent the ratchet, a pawl carried by the rod and engaging the ratchet, a spring normally holding the rod outwardly, and a projection carried by the piston rod and engaging the rod on the forward movement of the piston for rotating the ratchet for forcing the follower downward during each movement of the piston.

5. The combination with an original receptacle containing a follower having a screw working therethrough, a ratchet on the screw on the outside of the receptacle, of a housing secured to the receptacle and inclosing the ratchet, means for operating said ratchet for forcing the grease from the receptacle and means for receiving the grease from the receptacle and forcing it to a distant point.

6. The combination with an original receptacle having an elongated opening and a removable cover therefor and containing a follower having a screw extending on the outside of the receptacle, a ratchet carried by the screw, of a cylinder removably secured to the receptacle and having an opening communicating with the opening in the receptacle, a piston within the cylinder for forcing the grease therefrom and means operated by the reciprocation of the piston for operating the ratchet for forcing the grease from the receptacle.

7. The combination with an original receptacle having an elongated opening closed by a removable cover and means within the receptacle for forcing the grease therefrom, of a cylinder removably secured to the receptacle and having an opening communicating with the opening in the receptacle, a piston within the cylinder, means operated by the reciprocation of the piston for closing the communication with the receptacle and means operated by the piston for operating the means for forcing the grease from the receptacle.

8. The combination with an original re-

- ceptacle having an elongated opening closed by a removable cover and means within the receptacle for forcing the grease therefrom, of a stationary cylinder having an opening 5
6 communicating with the opening in the receptacle, a rotary cylinder within the stationary cylinder and having a corresponding opening, a piston within the rotary cylinder and held against rotation, a piston 10
10 rod carried by the piston and a spiral fin carried by the piston rod and adapted to rotate the rotary cylinder to bring the registering opening out of alinement during the movement of the piston for forcing the 15
15 grease from the cylinder, and means operated by the piston for actuating the means within the receptacle for forcing the grease therefrom.
9. An apparatus of the character described, comprising a support for a receptacle, a cylinder carried by the support and having an open upper face, a piston for forcing the grease from the cylinder, and means operated by the piston for closing 20
20 the upper open face of the cylinder during the time the piston is forcing the grease from the cylinder.
10. An apparatus of the character described, comprising a support for a receptacle, a cylinder carried by the support and having an open upper face, a rotary cylinder within the stationary cylinder and having a corresponding opening, a piston within the rotary cylinder and held against rotation, a piston 25
25 rod carried by the piston and a spiral fin carried by the piston rod and adapted to rotate the rotary cylinder to bring the registering openings out of alinement during the movement of the piston when forcing the 30
30 grease from the cylinder.
11. An apparatus of the character de- 35
35
- scribed, comprising a support for a receptacle, means whereby said receptacle can be secured to the support, a stationary cylinder carried by the support and having an open 40
40 upper face, a rotary cylinder within the stationary cylinder and having a corresponding opening, a piston within the rotary cylinder and held against rotation, a piston rod carried by the piston, a spiral fin carried by the piston rod and adapted to rotate the rotary cylinder to bring the openings out of alinement during the movement of the piston when forcing the grease from the cylinder, and means operated by the piston 45
45 rod for operating a discharging means carried by the receptacle. 50
50
12. In an apparatus of the character described, the combination with a receptacle, of a support detachably secured to one end 55
55 thereof and supporting the same, means carried by the support for forcing the contents of the receptacle therefrom, and means carried by the support for receiving the discharge of the receptacle and forcing it to a distant point. 60
60
13. In an apparatus of the character described, the combination with a receptacle, of a support detachably secured to one end 65
65 thereof and supporting the same, means carried by the support for forcing the contents of the receptacle therefrom, a cylinder carried by the support and receiving the discharge of the receptacle, and a piston for forcing the grease from said cylinder. 70
70
- In testimony whereof, I affix my signature, in the presence of two witnesses.

JAMES H. MONTGOMERY.
